UNITED STATES PATENT OFFICE.

PAUL OTTO, OF NEW YORK, N. Y.

DESIGN FOR A DECANTER.

Application filed November 28, 1927. Serial No. 24,313. Term of patent 7 years.

To all whom it may concern:

Be it known that I, PAUL OTTO, a citizen of the United States, residing at 448 Fourth Avenue, in the city, county, and State of New York, have invented a new, original, and ornamental Design for Decanters, of which the following is a specification, reference being had to the accompanying drawing, forming part thereof.

The figure as shown by the drawing is a front elevation of the decanter embodying my design.

I claim:

The ornamental design for a decanter, as shown.

The foregoing specification of my new and original design for decanters signed by me this 23rd day of November, 1927.

PAUL OTTO.
